UNITED STATES PATENT OFFICE

142,052

DESIGN FOR A PHONOGRAPH PICKUP ARM

Louis J. Wronke, Des Plaines, Ill., assignor to S. N. Shure, and Frances Shure, trustee, doing business as Shure Brothers, Chicago, Ill.

Application May 14, 1945, Serial No. 119,545

Term of patent 14 years

(Cl. D26—14)

To all whom it may concern:

Be it known that I, Louis J. Wronke, a citizen of the United States, residing at Des Plaines, in the county of Cook and State of Illinois, have invented a new, original, and ornamental Design for a Phonograph Pickup Arm, of which the following is a specification, reference being had to the accompanying drawing, forming part thereof.

Fig. 1 is a plan view of a phonograph pickup arm showing my new design;

Fig. 2 is a side elevational view;
Fig. 3 is a side elevational view;
Fig. 4 is an elevational view showing the left end portion; and

Fig. 5 is an elevational view showing the right end portion of the device.

I claim:

The ornamental design for a phonograph pickup arm, as shown.

LOUIS J. WRONKE.
